UNITED STATES PATENT OFFICE.

ALFRED BURKE, OF BROOKLYN, NEW YORK.

DIE.

1,294,391.

Specification of Letters Patent. Patented Feb. 18, 1919.

Application filed July 18, 1917. Serial No. 181,193.

To all whom it may concern:

Be it known that I, ALFRED BURKE, a citizen of the United States, residing at the borough of Brooklyn, in the city of New York, Kings county, and State of New York, have invented certain new and useful Improvements in Dies, of which the following is a specification.

This invention relates to an expanding die 10 for molding plastic materials.

One of the objects of the invention is to provide a die, comprising co-acting male and female members, for molding and finishing a completed article from a previously prepared blank.

Another object is to provide an automatically operating expanding core for spreading the material of the blank into registration with the mold cavity.

A further object is to provide the expanding-core with a rib for pressing a groove into the article during the molding operation.

A still further object is to provide a detachable plate interposed between the male 25 and female members to prevent the formation of a fin on the product, and to give access, by removal of the plate, to the mold cavity for withdrawal of the molded article.

To these ends, as well as to attain other 30 objects not specifically stated, my invention consists in the novel features of construction, arrangement and combination of parts, hereinafter described and particularly pointed out in the claims.

The die is intended to work on previously 35 formed blanks made of pyroxylin or similar material and provided with one or more narrow, elongated, openings. In operation of the die, the opening in the blank is placed over the expanding-core, which, upon expanding, spreads the opening to the required size and shape of the completed article, and charges the mold cavity with the surrounding material.

In the accompanying drawings, illustrating 45 a preferred embodiment of the invention, I have shown a die for making spectacle frames from blanks substantially of the character disclosed in Letters Patent No. 1,220,600 issued to me on March 27, 1917. It 50 will be understood, however, that I do not limit myself to this particular application of the invention for by changing the con-

figuration of the mold cavity the die may be adapted for use in making other articles. 55

Referring to the drawings Figure 1 is a plan view of the male member; Fig. 2 is a side elevation thereof; Fig. 3 is a sectional elevation of the female member taken on the line 3—3 of Fig. 4, showing the expanding- 60 core in contracted position; Fig. 4 is a plan view of the female member; Fig. 5 is a view of the rear face thereof as it appears after removal of the base, showing the guide slots in which the lugs of the expanding-core 65 work; Fig. 6 is a vertical section of the assembled die showing the parts in co-acting relation, with the core fully expanded and the detachable plate interposed between the male and female members; and Fig. 7 is a 70 horizontal section on the line 7—7 of Fig. 6 looking in the direction of the arrows.

The die consists of three general parts, namely, a male member A, a female member B, and a plate C detachably secured to the 75 face of the female member.

The male member A consists of a plate, to the under side of which is secured a framework comprising circular walls 1—1, extensions 2—2, and a bridge-piece 4. The 80 lower face of said framework is provided with a recess 5, having the shape of a spectacle-frame and constituting the upper section of the mold cavity. The central portions of the extensions 2—2 project below 85 their marginal edges, as seen in Fig. 2, so as to contact with the corresponding portions of the female member, when the two parts of the die are brought into the coacting relation shown in Fig. 6, whereby to press a 90 slot in the temple joint portion of the spectacle-frame. Disposed within the walls 1—1 are the wedge pieces 6—6, having tapered ends which extend below the lower edges of the walls and are adapted to penetrate the 95 core so as to expand the parts thereof.

The female member B is preferably composed of two plates 8 and 9, suitably secured together as by means of screws 10. In the face of the plate 8 is formed a recess 5', corresponding in position and shape to the recess 5 of the male member, and constituting the lower section of the mold cavity.

The said female member is provided with two expanding-cores, each consisting of four 105 segments, 11—11 and 12—12, arranged in

pairs and forming, when fully expanded, a complete circle of substantially the same diameter as that of the opening formed by the inner surface of the circular wall 1. The 5 inner face of each segment 11 is cut out in V-shape, forming a diamond shaped opening between each pair. Disposed in said opening are a pair of segments 12-12 having their lateral faces contacting with the 10 inner faces of the segments 11-11 and inclined at a corresponding angle. The upper, adjacent, edges of the segments 12-12 are divergently chamfered, as seen in Fig. 3, to facilitate penetration of the tapered end 15 of the wedge 6 therebetween. It is obvious that as the pair of segments 12-12 are moved from their initial contracted position, shown in Fig. 4, to their final expanded position, shown in Fig. 7, the pair of segments 11-11 will be simultaneously spread apart by sliding contact of the abutting surfaces.

The segments 11 are movably secured to the plate 8 by means of pins or lugs 13, 25 working in guide slots 14 and provided with heads 15, which ride in the transverse grooves 16. The segments 12 have pins or lugs 17 working in guide slots 18 and provided with heads 19 riding in the longitudinal groove 20. Retractile springs 21 connect the respective pairs of segments 11-11. Upon withdrawal of the wedge pieces 6, the springs act to draw said segments together and thereby to drive the segments 12-12 35 back to their initial positions.

In operation of the die, the blank (not shown) is placed on the female member B, with its openings in alinement with the cores, and is pushed down over the base of 40 said cores while the latter are in the contracted position shown in Fig. 4. Upon expansion of the cores, by penetration of the wedge pieces carried on the male member A, the openings of the blank will be spread 45 to the required shape and the surrounding material will be introduced into the lower section of the mold cavity in position to be molded by pressure of the upper section.

Near the base of the core segments 11 and 50 12 are located outwardly projecting ribs 22 which operate, as the core is expanded, to press a circumferential groove in the lens-receiving portion of the spectacle-frame. If desired, the ribs 22 may be omitted.

55 The plate C has its central portion cut away to leave an opening substantially corresponding in shape and size to the external configuration of the mold cavity. The plate is adapted to be detachably secured to the 60 face of the female member B with its opening in registration with the mold cavity, by means of the dowel-pins 23 or other suitable fasteners. When the plate is in place, as shown in Fig. 6, it constitutes the external 65 wall of the mold cavity and serves to pre-

vent the formation of a fin on the molded article. By removal of said plate, after the molding operation, the finished article is easily accessible for removal from the die.

I do not limit myself to the precise construction and arrangement of parts illustrated and described herein, as I am aware that various modifications may be made without departing from the scope of my invention.

75 What I claim as my invention and desire to secure by Letters Patent is:

1. A die for molding plastic material comprising a female member containing one section of the mold cavity and provided with 80 an expanding-core arranged so as to charge said section of the cavity with the material upon expansion of the core, and a male member carrying the other section of the mold cavity and provided with a projecting part 85 for expanding the core.

2. A die for molding plastic material comprising a female member containing one section of the mold cavity and provided with an expanding-core arranged so as to charge 90 said section of the cavity with the material upon expansion of the core, a male member carrying the other section of the mold cavity and provided with a projecting part for expanding the core, and a plate having 95 a portion cut away to form an opening of substantially the shape of the external configuration of the mold cavity, said plate being removably interposed between the male and the female members with its opening in 100 registration with the mold cavity.

3. A die for molding plastic material comprising a female member containing one section of the mold cavity and provided with an expanding-core composed of a plurality 105 of pairs of movable segments having inclined abutting surfaces arranged that the expansion of one pair will simultaneously expand the others, so as to charge said section of the cavity with the material upon 110 expansion of the core, and a male member carrying the other section of the mold cavity and provided with a projecting wedge-piece for expanding the segments of the core.

4. A die for molding plastic material comprising a female member containing one section of the mold cavity and provided with an expanding-core composed of a plurality of co-acting segments arranged so as to charge 120 said section of the cavity with the material upon expansion of the core, a male member carrying the other section of the mold cavity and having a projecting wedge-piece for penetrating the core to spread apart the 125 segments thereof, and means for returning the segments to their initial positions on withdrawal of the wedge-piece.

5. A die for molding plastic material comprising a female member containing one sec- 130

tion of the mold cavity and provided with an expanding-core composed of a plurality of co-acting segments arranged so as to charge said section of the cavity with the material upon expansion of the core, each segment having an outwardly extending circumferential rib near its base portion for pressing

5 a groove in the material upon expansion of the core, and a male member carrying the other section of the mold cavity and provided with a wedge-piece for expanding the segments of the core.
